(57) **CLAIM**

I claim the ornamental design for a distal radius plate, as shown and described.

DESCRIPTION

FIG. 1 is a top isometric view of a distal radius plate; FIG. 2 is a bottom isometric view of the distal radius plate of FIG. 1;

FIG. 3 is a top view of the distal radius plate of FIG. 1; FIG. 4 is a bottom view of the distal radius plate of FIG. 1; FIG. 5 is a front elevation view of the distal radius plate of FIG. 1;

FIG. 6 is a back elevation view of the distal radius plate of FIG. 1;

FIG. 7 is a left side elevation view of the distal radius plate of FIG. 1;

FIG. 8 is a right side elevation view of the distal radius plate of FIG. 1;

FIG. 9 is an environmental top isometric view of the distal radius plate of FIG. 1;

FIG. 10 is a top isometric view of a distal radius plate; FIG. 11 is a bottom isometric view of the distal radius plate of FIG. 10;

FIG. 12 is a top view of the distal radius plate of FIG. 10; FIG. 13 is a bottom view of the distal radius plate of FIG. 10;

FIG. 14 is a front elevation view of the distal radius plate of FIG. 10;

FIG. 15 is a back elevation view of the distal radius plate of FIG. 10;

FIG. 16 is a left side elevation view of the distal radius plate of FIG. 10;

FIG. 17 is a right side elevation view of the distal radius plate of FIG. 10; and,

FIG. 18 is an environmental top isometric view of the distal radius plate of FIG. 10.

The long dash-short dash-short dash-long dash lines in FIGS. 9 and 18 are directed to environment and form no part of the claimed design. All other broken lines, including the dash-dot-dash boundary lines are directed to unclaimed features and form no part of the claimed design.
